(57) **CLAIM**

The ornamental design for a hair extension holder, as shown and described.

DESCRIPTION

FIG. 1 is a front isometric view of hair extension holder showing a first embodiment of the new design in a closed configuration.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof.

FIG. 8 is a front isometric view thereof in an open configuration.

FIG. 9 is a left side elevation view thereof in the open configuration.

FIG. 10 is a front isometric view of hair extension holder showing a second embodiment of the new design in a closed configuration.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan view thereof.

FIG. 16 is a bottom plan view thereof.

FIG. 17 is a front isometric view thereof in an open configuration; and,

FIG. 18 is a left side elevation view thereof in the open configuration.

The broken lines in the drawings are for the purpose of illustrating portions of the hair extension holder that form no part of the claimed design.
